Stuart W. Sizer, Harbert, Mich., and Robert L. Deschamps, West Chicago, Ill., assignors to Heath Company, St. Joseph, Mich., a corporation of Delaware

Continuation of design applications Ser. No. 9,770 and Ser. No. 9,776, both dated Dec. 14, 1967. This application Dec. 6, 1968, Ser. No. 14,826

Term of patent 14 years

Int. Cl. D14—02

U.S. Cl. D26—5

FIG. 1

FIG. 2

FIG. 3

FIG. 4

FIG. 5

FIG. 6

FIGURE 1 is a perspective view of a cabinet for housing electrical apparatus showing our new design;

FIGURE 2 is a top view of the cabinet of FIGURE 1;

FIGURE 3 is a side elevational view of the cabinet of FIGURE 1;

FIGURE 4 is a perspective view of a variation of the FIGURE 1 cabinet for housing electrical apparatus;

FIGURE 5 is a top view of the cabinet of FIGURE 4; and

FIGURE 6 is a side elevational view of the cabinet of FIGURE 4.

The undisclosed side of the cabinet shown in FIGURES 1-3 is a mirror image of the side shown, and the rear is substantially flat and plain in appearance except for conventional hooks shown in broken lines.

The undisclosed side of the variation of cabinet shown in FIGURES 4-6 is a mirror image of the side shown, and the rear is substantially flat and plain in appearance.

The dominant features of the design reside in the portions shown in full lines.

The characteristic feature of the design resides in the

arrangement and particular configuration of the handles on either side of the cabinet as shown.

This is a continuation application of our copending applications, Ser. Nos. D. 9,770 and D. 9,776, filed Dec. 14, 1967, and now abandoned.

What is claimed is:

The ornamental design for a cabinet for housing electrical apparatus, substantially as shown and described.
